US0D1037376S

(12) **United States Design Patent** (10) **Patent No.:** **US D1,037,376 S**
Carruthers (45) **Date of Patent:** **** Jul. 30, 2024**

(54) **FOOT PEDAL FOR A CLIMBING EXERCISE MACHINE**

(71) Applicant: **CLMBR1, LLC**, Englewood, CO (US)

(72) Inventor: **Nathaniel Carruthers**, Austin, TX (US)

(73) Assignee: **CLMBR Holdings, LLC**, Austin, TX (US)

(**) Term: **15 Years**

(21) Appl. No.: **29/776,740**

(22) Filed: **Mar. 31, 2021**

(51) **LOC (14) Cl. 21-02**

(52) **U.S. Cl.**

USPC **D21/694; D12/125**

(58) **Field of Classification Search**

USPC D21/662, 673, 679, 682, 6, 83, 684, 691, D21/692, 694, 698, 798, 826, 663, 670, D21/685; D12/114, 125

CPC . Y10T 74/2164; Y10T 74/2168; A63B 23/08; A63B 23/10; A63B 69/16

(57) **CLAIM**

The ornamental design for a foot pedal for a climbing exercise machine, as shown and described.

DESCRIPTION

FIG. 1 is a top perspective view of a foot pedal for a climbing exercise machine showing my new design;

FIG. 2 is a bottom perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

1 Claim, 8 Drawing Sheets
